(57) **CLAIM**

The ornamental design for a wheelchair wheel cover, as
shown and described.

DESCRIPTION

FIG. 1 is a perspective view of a wheelchair wheel cover
according to an exemplary embodiment of the present
invention;

FIG. 2 is a front elevational view of the cover of FIG. 1;
FIG. 3 is a rear elevational view of the cover of FIG. 1;
FIG. 4 is a right side elevational view of the cover of FIG.
1, with the left side being a mirror image thereof;
FIG. 5 is a top plan view of the cover of FIG. 1;
FIG. 6 is a bottom plan view of the cover of FIG. 1; and,
FIG. 7 is a sectional view of the cover of FIG. 5 taken along
lines 7-7 of FIG. 5.
